[57] CLAIM

The ornamental design for a waste receptacle, as shown and described.

DESCRIPTION

FIG. 1 is a top and front perspective view of a waste receptacle showing new design, the rear view being identical to the front;

FIG. 2 is a side elevational view thereof, the opposite side elevational view being a mirror image of that shown;

FIG. 3 is a top and front perspective view of a second embodiment of the waste receptacle; and

FIG. 4 is a side elevational view of FIG. 3, the opposite side view being a mirror image of that shown.

The undisclosed bottom is flat and unornamented.

FIG.1

FIG.2
